UNITED STATES PATENT OFFICE.

JOHN P. SWAN, OF PLYMOUTH, FLORIDA.

SPRINKLER SYSTEM.

Application filed September 12, 1925. Serial No. 55,896.

This invention relates to improvements in sprinkler systems. More especially it relates to an improved construction of the distribution pipes of such a system and combination of pipes therein, resulting in the possibility of using smaller pipes and these concealed within the natural partitions of the building, thereby leaving the appearance of the risk undisturbed, the system being at the same time arranged as a single unit having protective capacity equal to that of a single riser unit of the style now customarily installed.

It is common practice, both when installing a sprinkler system in a new building and when adding such a system to an old structure, to provide a vertical trunk or distributing pipe of suitable size, called a riser, which at each floor feeds a large horizontal branch pipe from which at frequent intervals horizontal offshoots or sub-distribution pipes lead, each serving a number of adjacent sprinkler heads. Thus the primary distribution is vertical, to the several floors; the secondary distribution is horizontal, usually along the axis of the area covered; and the tertiary stage is horizontal. Each riser or trunk with its branches, sub-distribution pipes and sprinklers constitutes a unit system. The riser is a large pipe, most frequently of six inch diameter. Each said branch has to be large and heavy; and the net work of piping on each floor, carried just under the ceiling, has pipes too large in diameter and is too complicated in layout to be installed between the ceiling and the floor above. It is heavy as a whole and imposes a constant stress upon the floor beams; is unsightly and disfiguring, especially in an office building or mercantile establishment; and may be a source of trouble and inconvenience if other fixtures, or apparatus, such as shafting, pulleys, etc., are to be supported from the ceiling.

It is an object of the present invention to eliminate these large horizontal feeders on each floor and some of the horizontal offshoots, and to provide, either at the top of the building, in the attic if there be one, or in the basement, if preferred, a single trunk line of horizontal pipes from which the water is distributed to the sprinklers by small vertical risers concealed within the partitions, and by such horizontal off-shoots as may be needed, arranged in the space between a floor and the ceiling immediately

under it. It is intended to limit the number of heads on each floor fed by the same vertical riser, and to make this riser of such size as will amply feed the limited number of heads. It is a result of the invention that the quantity of piping required in a risk is less, and for the most part is of a smaller size, though ample for effective sprinkler protection. This results in a lower initial cost, greater ease in handling during installation, and smaller added load upon the building. The latter feature is of especial importance in the case of wet pipe systems, where the constant weight of the water must be added to the weight of the pipes themselves.

These objects and the results which characterize the construction herein disclosed are attained by connecting to a supply source a trunk pipe for making the primary distribution horizontally over all floors of the area served by the unit, which trunk may preferably be located either next to the roof or in the basement. From this trunk the branches or secondary distributing pipes extend vertically within the partitions and have off-shoot that preferably run between a floor and the adjacent ceiling to sprinkler heads arranged in groups and exposed over the area to be protected. Each group is made up of a limited number of heads or nozzles and one such group on each floor of the building is connected to the same vertical distributing pipe, which is of a size and capacity to supply only one group at a time. As the sprinkler heads operate only in the vicinity where the fire occurs, the vertical distributing pipe need only be of a capacity to supply the particular group protecting that area, and thus it may be small enough to be concealed within the partition. If the single vertical supply riser is placed in a shaft or other concealed conduit the entire system will be out of sight except for the exposed heads or nozzles which necessarily project through the ceiling or walls.

It is intended that the patent shall cover, by suitable expression in the appended claims, whatever features of patentable novelty exist in the invention disclosed.

In the accompanying drawings:

Figure 1 is a plan of a layout of pipes in a portion of the attic of a building;

Figure 2 is a plan of the layout for an intermediate story between a floor and its adjacent ceiling;

Figure 3 is a plan like Figure 2 on a level between the second floor and ceiling of the first floor; and

Figure 4 is an elevation in section on line 5 4-4 of Figure 1 on a larger scale.

Referring to the drawings, which as a whole represent a single unit system and which illustrate how it may be applied in a building which has no partitions in a space 10 of considerable area on the first floor, a water main (not shown), assumed to be below the first floor and there leading from any suitable source of supply, is connected by a vertical pipe 12, which is not a distributing pipe but is a mere conduit (but in size or capacity may be comparable to a distributing riser of the customary type above described), with a trunk system of horizontal feeders 14 which constitute the primary 20 distribution stage of the system and are arranged in the space between the ceiling of the top floor or attic floor and the roof. From these feeders 14, smaller pipes 16 are connected to sprinkler heads 18, projecting 25 through the said ceiling, and vertical branch pipes 20 extend within a partition 21 to just above the first floor ceiling 22.

In the spaces between a floor and the ceiling next under it are horizontal off-shoots 30 24 which connect with the sprinkler heads or nozzles exposed beneath that ceiling.

They are arranged so that only a limited number of sprinkler heads at each line will be supplied by the same vertical pipe. As 35 shown, not more than six are connected to any one of the horizontal off-shoots. By this arrangement of the sprinkler heads the vertical pipes 12 need only have a capacity for supplying one group, this being sufficient 40 because a fire almost never starts in two different places, one above the other at the same time. Since only one group or part of one group of sprinklers at a particular level will ever be called into service, it does not 45 matter that similar groups above and below are connected to the same vertical pipe, because these similar groups will not be drawing water at the same time the discharging heads are in action.

50 Obviously the horizontal feed pipes 14 may be placed in the basement of a building if desired, if the first floor has partitions through which the secondary distributing pipes 20 can rise, in which case the supply 55 main would join the trunk distribution 14 direct and the vertical pipes 20 would extend thence upward through the partitions with the horizontal off-shoots connected thereto as before described. If the building 60 illustrated had a basement for which sprinkler protection were needed and this basement were inaccessible to the vertical pipes 20 depending from the attic, because of there being no partition in the first floor 65 through which the pipes could be carried

down, the needed basement sprinkler protection could be had by tapping the pipe 12 in the basement (not illustrated) and making a horizontal branch in the manner here-tofore customary, such being an arrangement not embodying the present invention.

In the case of a building so long that a trunk 14 of adequate size would be inconveniently large, the whole may be covered by using as many separate unit systems, or as frequent supply pipes 12, like that herein illustrated, as may be desired or necessary for covering the whole.

I claim as my invention:

1. A sprinkler system unit for a building, comprising, in combination, a horizontal distributing trunk for the ground area served by said unit; vertical distributing branches from this trunk, spaced at intervals over the area protected by the unit, each extending several floors and each being of less cross sectional area than would be proper for a single main riser of a standard sprinkler system; horizontal off shoots from each of the vertical branches at the several floors of said ground area, the off shoots from different vertical pipes at each floor collectively but not individually covering said floor; and sprinkler heads connected to the off shoots.

2. A sprinkler system unit for a building, comprising, in combination, a horizontal distributing trunk for the ground area served by said unit; vertical distributing branches from this trunk; horizontal off shoots from each of the said vertical distributing branches at different levels; and a group of sprinkler heads connected to each said horizontal off shoot; each said vertical branch being of less cross-sectional area than would be proper for a single main riser of a standard sprinkler system, but having capacity suitable for supplying the largest one of its connected groups of sprinkler heads, and insufficient for supplying all of its said connected groups.

3. A sprinkler system unit for a building comprising in combination, a plurality of vertical distributing pipes within the unit, each being of less cross-sectional area than would be proper for a single main riser of a standard sprinkler system, and the plurality of them being distributed over the ground area protected by the unit; sprinklers arranged in small groups, each said small group having individual connection to one of said vertical pipes; there being a succession of said small groups connected to the same vertical pipe at successive floors; and the sprinkler protection at each floor being composed of a plurality of said small groups individually connected to different vertical pipes in the unit.

4. A sprinkler system unit for a building comprising sprinkler heads arranged in a plurality of groups for each floor of the

building; and distributing pipes connecting individual sprinkler groups in vertical series; the said distributing pipes being scattered over the unit of area protected and 5 being themselves connected in horizontal series and being each of less cross sectional area than would be proper for a single main riser of a standard sprinkler system.

5. A combination of distribution pipes in 10 a sprinkler system unit comprising a trunk distribution pipe and connections and sprinklers fed thereby, wherein the larger pipes in said connection between the trunk and the sprinklers extend vertically and are 15 severally of less cross sectional area than would be proper for a main riser of a standard sprinkler system.

6. A sprinkler system for a building comprising, in combination, a horizontal feeder 20 unit extending along the ground area served by the system and serving for primary horizontal distribution for a plurality of floors thereof; vertical distributing pipes extending from this horizontal unit, each to several 25 floors and each for the several partial horizontal areas of the floors which it serves and being severally of less cross-sectional area than would be proper for a main riser of a standard sprinkler system; and sprinklers on the several floors, each with short 30 horizontal pipe in said partial areas connecting the sprinklers to said vertical pipe.

7. A sprinkler system unit for a building having a plurality of floors, in which unit

there is a main horizontal distribution element comprising a series of interconnected horizontal distributing pipes arranged at one level and extending over ground area of the unit; a multiplicity of sprinkler heads scattered over each floor, and of horizontal sub-distribution elements therewith at each floor feeding the sprinklers; and a multiplicity of vertical distribution elements scattered over said area, each being of less cross sectional area than would be proper for a single main 45 riser of a standard sprinkler system and each extending from the said main horizontal element through the several floors and connected directly to said horizontal sub-distribution elements at the several floors. 50

8. A sprinkler system unit for a building having a plurality of floors, comprising a primary distributing trunk element for the ground area of the unit, comprising a system of horizontal pipes arranged at one 55 level; a secondary distribution, comprising elements passing vertically through the several floors, each of which elements is of less cross sectional area than would be proper for a single main riser of a standard sprinkler system; tertiary distribution comprising horizontal off-shoots from the secondary at each floor; and sprinkler heads connected to the tertiary elements. 60

Signed at Plymouth, Florida, this thirty-first day of August, 1925. 65

JOHN P. SWAN.
